P. G. LESSMANN.

ALARM FOR EIGHT DAY CLOCKS.
APPLICATION FILED NOV. 29, 1918.

1,333,178.

Patented Mar. 9, 1920.

UNITED STATES PATENT OFFICE.

PAUL G. LESSMANN, OF CHICAGO, ILLINOIS.

ALARM FOR EIGHT-DAY CLOCKS.

1,333,178.

Specification of Letters Patent. Patented Mar. 9, 1920.

Application filed November 29, 1918. Serial No. 264,577.

To all whom it may concern:

Be it known that I, PAUL G. LESSMANN, a citizen of the United States, residing at Chicago, in the county of Cook and State 5 of Illinois, have invented certain new and useful Improvements in Alarms for Eight-Day Clocks, of which the following is a specification.

My invention relates to an alarm attachment for eight day clocks.

While I generally aim to reduce the cost of manufacture, simplify and render the operation of such a device more efficient, yet a particular object is to provide a mechanism utilizing an electrically operable alarm, for instance a bell, for which the electric circuit is closed by means associated with the hour hand operating means of the clock and to provide the particular form of circuit establishing means as well as the other details of construction shown in the accompanying drawings and hereinafter described and claimed.

In the said drawings:—

Figure 1 is a front elevation of the parts of my attachment which are disposed within the clock casing;

Fig. 2 is a side elevation of the parts of Fig. 1, together with a portion of the back 30 of the clock;

Fig. 3 is a fragmentary rear view of a clock utilizing my improvements;

Fig. 4 is a diagrammatic view of the electric circuit means employed;

Fig. 5 is a vertical sectional view through the plunger contact device employed;

Fig. 6 is a vertical sectional view through the other contact device employed, and

Fig. 7 is a vertical sectional view on the 40 line 7—7 of Fig. 6.

In considering the drawings, it is to be understood that most of the parts of the clock have been omitted, since they form no part of the invention and would only tend to obscure the disclosure. The parts of the clock therefore which are shown, are to be taken as diagrammatic, and given only for an understanding of the invention.

The alarm employed may be any suitable 50 type of bell as suggested at 8, and which may be mounted on one side of the clock frame as at 9, and in the rear of one of the facing strips as at 10, as shown in Fig. 3. The electric battery employed is designated 55 11, preferably resting on the support 12 for the clock, and beneath the base wall 13 of

the clock casing, surrounded by the riser walls 14 of said casing. A conductor wire 15 leads from one pole of the battery 11 to a plunger contact device A which cooperates with a contact device B to establish the electric circuit. The circuit is completed by a conductor formed in a section 16 which leads from the contact device B to the bell 8 and by a section 17 which leads 60 from the bell 8 to the other pole of the battery 11. In the section 17, a suitable switch 18 may be provided. As seen in Fig. 3 the switch 18 may be mounted on one of the risers 14.

Contact device A comprises a suitably shaped stud 19 having a bore 20 provided with screw threads therein in order to receive the shank of a set screw 21 which passes through the back of the clock 22, in 70 Fig. 2, and engages the screw threads in the opening 20. The stud 19 is thus secured in place and preferably at the angle shown in Fig. 1. If desired, washers or disks 23 may be placed against the opposed 75 faces of the back of the clock 22 as shown in Fig. 2. Also the head of the set screw 21 is in conducting relation with the wire 15, and preferably clamped against one of the washers 23. Slidable diametrically of 80 the stud 19 is a plunger contact 24. This contact slides in an enlarged diametric opening 25 of the stud being guided by plugs 26 and 27 soldered or otherwise rigidly fastened to the stud within the opening 25. 85 Secured to the contact 24 and slidable therewith, is a disk or projection 28. Surrounding the contact within the opening 25 is an expansive coil spring 29, one end of which 90 engages the disk 26 while the other end engages the projection 28. The spring 29 normally urges the projection 28 into contact with the projections 27, and the sliding contact 24 into projected position as shown in 95 Figs. 1, 2 and 5.

Said contact 24 has a link 30 loosely connected thereto by means of an eyelet 31. This link 30 in turn is pivoted or loosely connected to a lever 32, as at 33. This lever, at one end, is pivoted as at 34, to the frame 105 35 of the clock works, and which has been but fragmentarily shown. Lever 32 rests on a cam 36 and is adapted to be permitted to be moved by said cam from the dotted line position of Fig. 1, where the contact 24 is 110 retracted to the full line position of Fig. 1, where the contact 24 is projected. Cam 36,

is mounted to turn with a spindle 37, which is suitably driven to turn the hour hand of the clock, which is mounted thereon, an illustration of which has been omitted for the sake of clearness. It will be seen therefore that as the spindle 37 turns the cam 36 will turn to vary the position of the lever 32, which is always urged downwardly by spring 29 bearing against the projection 28 and the connection of the lever to the contact by means of the link 30. The usual spindle which turns independently of spindle 37, in order to operate the minute hand of the clock, is shown at 38. It may be mentioned, that a dial 39 is provided to set the alarm, being formed integral with or connected to the cam 36 by means of a short connecting sleeve 40. This device 36-39-40 merely frictionally engages the spindle 37. The degree of friction however is sufficient that the spindle 37 will move the device therewith but that the device may be turned independently of the spindle 37, without disturbing its position or the position of the hour hand moved thereby.

The contact device B comprises a stud 41 having an opening 42 provided with screw threads therein with which engage the screw threads of the shank of a set screw 43, passing through the back 22 of the clock. Washers or disks 44 may be placed against the opposite faces of the back 22 as shown in Fig. 2, and the conductor 16, may be fastened in place or clamped beneath the head of the set screw 43. Stud 41 mounts a contact 45, with which the contact 44 engages to establish the electric circuit. Since the distances between the studs 19 and 41 may vary in attaching the device to clocks, contact 45 is preferably adjustable relative to the contact 24. To this end contact 45 slides in a diametric opening 46 of the stud 41, being clamped in the desired adjusted position by means of a set screw 48 carried by the stud. To facilitate engagement of the contact 24 with the contact 45, the last mentioned contact is preferably dished or concaved as at 47.

It will be understood that the parts of the devices A and B should be of conducting material, in order to establish the electric circuit. Also that while both of these devices are shown at an angle, as in Fig. 1, this is done merely to accommodate attachment to one style of clock and hence no limitation is to be inferred.

In operation, the dial 39 is turned relative to the spindle 37, so that the lever 32 will be pulled downwardly by the spring 29, off of the lobe or highest point of the cam, to the lowest point of the cam when the

alarm is to be given. When the lever makes the fall referred to, spring 29 by bearing against the projection 28 will urge the contact 24 into abutting or striking relation with the contact 45, thus closing the electric circuit through the bell 8, causing it to ring to give the alarm. It will be understood of course that before setting the dial 39 or thereafter, switch 18 is closed. After the alarm is given, it will continue, until the switch 18 is manually opened. Thereafter the dial 39 may be reset as will be clearly understood.

Since merely one preferred embodiment of the invention has been illustrated and described, it is to be understood that changes in the details of construction thereof may be made within its spirit and scope.

I claim:

1. An alarm mechanism of the class described having electric circuit means including contacts and an alarm, a stud movably mounting one of said contacts, means to move the contact, and a spring bearing against the stud and against the contact. 80

2. An alarm mechanism of the class described having electric circuit means including contacts and an alarm, one of the contacts being movable relatively to the other contact to control the giving of the alarm, a stud mounting one of the contacts, said stud being turnable relatively to the other contact, and means to secure said stud to a support. 90

3. An alarm mechanism of the class described including a lever, a cam which said lever follows, a link device, a contact connected to said link device, a stud, means to fasten the stud to a support and for axial adjustment, said stud having an opening in 95 which the contact slides, abutment members adjacent the ends of said opening, abutment means on the contact to engage the lowermost abutment member, a spring surrounding the contact and engaging the uppermost 100 abutment member and the abutment means of the contact, a second contact, said second contact being engageable by the first contact to give the alarm, a stud, means to fasten the stud to a support and for axial adjustment, and means to adjustably fasten the second mentioned contact to the section mentioned stud, whereby its position may be varied relative to the movable contact. 110

In testimony whereof I have affixed my 115 signature in the presence of two witnesses.

PAUL G. LESSMANN.
